CLAIM

The ornamental design for a cable organizer, as shown and described.

DESCRIPTION

FIG. 1 is front perspective view of a cable organizer of my new design;

FIG. 2 is a front plan view thereof;

FIG. 3 is a rear plan view thereof;

FIG. 4 is a right side view thereof;

FIG. 5 is a left side view thereof;

FIG. 6 is a top plan view thereof; and,

FIG. 7 is a bottom plan view thereof.
